(57) CLAIM

The ornamental design for an exercise apparatus, as shown and described.

DESCRIPTION

FIG. 1 is a front perspective view of the exercise apparatus showing the new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The single broken lines shown along the perimeter of the handle of the exercise apparatus in FIGS. 1, 4, and 5 illustrates seaming in the fabric.

The appearance of any portion of the exercise apparatus between the break lines forms no part of the claimed design. The stippling in the drawings represents shading and not a surface pattern.
